ADJUSTABLE LOCK STRIKE

Charles B. Flora, Danville, Va.

Application August 10, 1936, Serial No. 95,214

7 Claims. (Cl. 292—340)

This invention relates to locks and latches and more particularly to a lock strike for use on doors and similar closures.

The object of the invention is to provide a lock strike of simple and inexpensive construction especially designed for use in connection with locks of the sliding bolt type and which may be readily adjusted both vertically and horizontally to aline the keeper and bolt without the necessity of removing the lock strike from the door jamb.

A further object of the invention is to provide a lock strike comprising an inner attaching plate and an outer strike plate adjustably mounted thereon, said plates being provided with inter-engaging parts normally and yieldably held in contact with each other.

A further object is to provide a lock strike having threaded pins connecting the inner and outer plates thereof and having coiled springs surrounding said pins so that by moving the outer strike plate against the tension of the springs, said strike plate may be readily adjusted to aline the keeper and sliding bolt and the parts securely held in adjusted position.

A still further object of the invention is generally to improve this class of devices so as to increase their utility, durability and efficiency.

In the accompanying drawing forming a part of this specification and in which similar numerals of reference indicate corresponding parts in all the figures of the drawing,

Figure 1 is a front elevation of an adjustable lock strike constructed in accordance with the present invention.

Figure 2 is a vertical sectional view taken on the line 2—2 of Figure 1.

Figure 3 is a perspective view showing the several parts comprising the adjustable lock strike separated and ready to be assembled.

Figure 4 is a plan view looking at the inner face of the adjustable strike plate.

The improved lock strike forming the subject-matter of the present invention may be used in connection with any type of swinging closure, and, by way of illustration, is shown attached to the jamb 5 of a standard door, said jamb being provided with the usual mortise 6.

The device comprises an attaching plate 1 preferably formed in two sections 8 and 9 to facilitate the manufacture thereof, said sections being welded, riveted or otherwise permanently secured together so as to form, in effect, an integral structure. The outer face of the inner section 9 is formed with a series of longitudinal

and transverse teeth or corrugations 10 and 11 and said inner section 8 is provided with a rectangular seating recess 12 through which the teeth or corrugations are visible. After the sections 8 and 9 are secured together, openings 13 are formed therein for the reception of screws or similar fastening devices 14 by means of which the attaching plate may be secured to a door jamb. Each section of the attaching plate is also formed with a lateral tongue 15 for engagement with the spring latch bolt of a door lock.

Fitted within the seating recess 12 and adjustable longitudinally and horizontally of the door is a strike plate 16 having upper and lower openings 17 and 18 formed therein for the reception of the spring latch bolt and the sliding lock bolt of the lock, respectively, said openings being separated by an intermediate web 19, as shown. The inner face of the strike plate 16 is formed with horizontal and longitudinal teeth or corrugations 20 corresponding to the teeth on the attaching plate so that after the strike plate is adjusted to the desired position, the inter-engaging teeth will hold said strike plate in a set position.

The rear section 9 of the attaching plate is formed with upper and lower openings 21, and extending loosely through said openings are headed pins 22, the outer ends of which are threaded into the strike plate, as indicated at 23. The diameter of each opening 21 is considerably larger than the diameter of the pin 22 extending through the same so as to permit the strike plate 16 to be shifted both longitudinally and laterally to aline the opening 18 with the sliding lock bolt of the door lock should the door sag or the sliding lock bolt of the lock fail to enter the opening 18.

Surrounding each pin 22 is a coiled spring 24, one end of which bears against the head of the adjacent pin, while the other end thereof rests against a washer 25 spanning the adjacent opening 21. The springs 24 serve to normally and yieldably hold the teeth on the strike plate 16 and attaching plate 7 in engagement with each other, but when a slight outward pull is exerted on the strike plate against the tension of the springs 24, said strike plate may be shifted either horizontally or longitudinally of the door to center the opening 18 with respect to the sliding lock bolt of the lock. The pins 22 project within the mortise 6 of the door so as to house and protect the same and not to present an unsightly appearance.

Should the sliding lock bolt on the door lock fail to register with the opening 18 in the strike

plate due to sagging of the door or other conditions, it is merely necessary to grip the connecting web 19 with a pair of pliers and exert a slight outward pull thereon against the tension of the 5 springs 24 until the teeth on the attaching plate and strike plate become disengaged when, by moving the strike plate 16 either vertically or laterally of the door jamb, the opening 18 in the strike plate may be properly aligned with the sliding lock bolt of the door lock, as will be readily understood. When the proper adjustment of the 10 strike plate has been effected, the springs 24 will automatically return the strike plate 16 to normal position and in which position the teeth will inter- 15 engage and prevent further movement of said strike plate.

While it is preferred to make the attaching plate in two sections, it will, of course, be understood that said attaching plate may be of integral 20 construction, if desired. It will also be understood that the lock strikes may be made in different sizes and shapes to accommodate any style or type of door without departing from the spirit of the invention.

Having thus described the invention, what is claimed as new is:

1. A lock strike comprising an inner attaching plate, an outer strike plate having face to face engagement therewith, and yieldable means for holding the strike plate in a set position and permitting shifting thereof to another set position in its initial plane.

2. A lock strike comprising an inner attaching plate and an outer horizontally and longitudinally 35 adjustable strike plate fitting against the outer face thereof, said plates having confronting faces provided with inter-engaging members, pins extending through said plates, and springs surrounding the pins for normally and yieldably holding the strike plate in a set position.

3. A lock strike comprising a body having a seating recess and provided with longitudinal and transverse teeth, a strike plate adjustably mounted within the seating recess and provided with teeth 45 adapted to engage the teeth on the body, pins secured to the strike plate and loosely extending through the body plate, and coiled springs surrounding the pins for normally and yieldably holding the teeth on the strike plate and the body 50 in engagement with each other and maintaining the strike plate in an adjusted position.

4. A lock strike comprising a body having a seating recess formed therein and provided with longitudinal and transverse teeth, there being 55 spaced openings formed in the body and extending through said teeth, a strike plate adjustably mounted within the seating recess and provided with teeth coacting with the teeth on the body,

pins secured to the strike plate and extending through the openings in the body and having heads at their free ends, washers fitted around the pins and spanning the openings in the body, and coiled springs fitted around the pins and bearing against the heads of said pins and the adjacent washers to maintain the strike plate in an adjusted position.

5. A lock strike comprising a body having a laterally extending tongue and provided with a seating recess and a bolt receiving opening in the recess, the inner wall of the recess being formed with longitudinal and transverse teeth about the bolt receiving opening, there being spaced fastener receiving openings formed in the body above and below the bolt receiving opening and intersecting the adjacent teeth, a strike plate adjustably mounted in the seating recess and provided with corresponding teeth for engagement with the teeth on the body, pins threaded in the strike plate and extending loosely through the openings in the body and formed with heads at their free ends, washers fitted over the pins and bearing against the rear face of the body about the fastener receiving openings therein, and a coiled spring interposed between each washer and the head of the adjacent pin.

6. A lock strike comprising a body having a seating recess therein and provided with a bolt receiving opening and teeth about the opening, a strike plate adjustable longitudinally and laterally within the seating recess and provided with teeth inter-engaging the teeth of the body, pins rigidly secured to the strike plate and extending loosely through the attaching plate, and resilient means carried by the pins for normally and yieldably holding the strike plate in an adjusted position with the teeth on the strike plate and attaching plate in gripping engagement with each other.

7. A lock strike comprising a body formed of rigidly united front and rear plates, the front plate being formed with an opening exposing a portion of the rear plate and together therewith providing a seating recess, the exposed portion of the rear plate having a roughened surface visible 45 through the opening of the front plate, an adjustable strike plate seated in said recess and provided with a roughened surface coacting with the roughened surface on the rear plate, guide pins secured to the strike plate and passing loosely 50 through openings in the rear plate, and springs surrounding the pins and bearing against the rear face of the rear plate for normally and yieldably holding said roughened surfaces in gripping engagement with each other to maintain the strike 55 plate in an adjusted position.
